UNITED STATES PATENT OFFICE.

PERCY ROBERT DOBSON, OF ROCKYFORD, ONTARIO, CANADA.

DOOR-OPERATING MECHANISM.

Application filed September 13, 1926. Serial No. 135,209.

This invention relates to improvements in automatic door operating mechanism and the objects of the invention are to provide a mechanism of this description for garages adapted to automatically open, close, lock and re-open doors either mounted on hinges or rollers and so constructed as to be automatically operated by means of cranks operable by a vehicle passing thereover.

Further objects are to provide automatic mechanism of this description that will obviate the necessity of the driver of a vehicle dismounting to open or close the doors of a garage, warehouse, gates or the like.

A still further object is to provide automatic door opening mechanism that will, under all conditions of weather be found to satisfactorily open and close doors or gates by the travel of a vehicle thereupon.

With the foregoing and other objects, hereinafter more fully referred to, in view, the invention consists essentially in the combination with a door, of crank-operated mechanism for opening, closing, locking and unlocking said door from a distance on a vehicle passing over the cranks.

Referring now to the drawing in which like characters of reference indicate corresponding parts in each figure,

Figure 1 is a sectional elevation of the door operating mechanism as applied to a garage with the doors in open position.

Figure 2 is a plan view of Figure 1.

Figure 3 is a perspective view of the operating mechanism.

Figure 4 is a sectional plan view of a garage showing the doors in closed position.

Figure 5 is a side elevation of the outside operating member.

Figure 6 is an end view of Figure 5.

Figure 7 is a side elevation of the inside operating member.

Figure 8 is a perspective view of a slotted collar associated with the operating member.

Figure 9 is a plan view of the door operating mechanism.

Figure 10 is a modified form of operating mechanism.

Figure 11 is a further modified form as used in a restricted area such as a narrow lane-way.

In the example of my invention disclosed 10 designates a garage and 11 and 12 the doors. The mechanism adapted to be operated by pressure from the wheels of an 55 automobile or the like, indicated by the dotted lines in Figure 1, comprises trip members 13 and 14 arranged outside and inside the garage doors respectively.

To open the doors the member 13 is engaged by the front wheels of the vehicle and consists of a horizontally arranged, rotatable shaft 15 suitably supported in bearing brackets 16 on blocks 17. On this shaft 60 is rigidly mounted in any suitable manner crank 19—crank 18 is hinge mounted to shaft 15 and is returned to right angles to 19 by springs 50, the crank members 18 and 19, 65 are so arranged that when one of them 18 is in a vertical or engaging position, as illus- 70 trated in Figure 3, the other 19 will be in a horizontal or flat position. Crank 19 is designed on being engaged by the front wheel of an automobile to rotate the shaft 15, as hereinafter more fully described. On 75 the inner end of this shaft 15 is a collar or sleeve 20 rotatably secured thereto by means

of a pin 21 and having integral therewith a crank arm 22 to which is connected in any suitable manner a horizontally extending 80 shaft 23, the other end of which is connected to a gear 24 designed to mesh with a gear 25 in turn rigidly connected to a vertical shaft 26 provided with cranks 27 and 28 to which

are attached pitmen 29 and 30 in turn connected to the doors 11 and 12 of the garage 85 10. Also connected to the gear 24 is a horizontal shaft or rod 31 the other end of which is connected to a vertical crank arm 32 similar to the member 22 and similarly mounted 90

on a shaft 33 counter to the shaft 15 and provided with a crank operating member 34

adapted to be engaged by the wheel of an automobile to rotate the shaft 33.

From the foregoing it will be seen that in 95 the position as illustrated in Figure 2, in which the doors are open the trip crank member 18 outside the doors on the shaft 15 will be in an upright position while

the crank member 34 will also be in up- 100 right position. Then, as the machine

enters into the garage, the member 34

will engage with the wheels of the vehicle causing the shaft 33 to rotate moving the shaft 31 forward and through the gears 25 and 24 rotating the shaft 26 to close the doors 11 and 12. At the same time the shaft 23 will move outwardly rotating the shaft 15 to cause the trip crank 19 to assume a vertical position and at the same time to cause the trip 18 to assume a laying position which is reversed when crank 34 is forced down and back to open the doors thus action is caused by cable 46, 19 is then ready for engagement with the rear wheel of the vehicle when it emerges from the garage to tip 19 upright, so front wheels will engage with 19 and close the doors and lock them.

The crank members 34 and 18 are spring actuated as at 35 and 51 by springs 36 and 50 on the shafts 33 and 15 to retain them in normal upright position and crank 19 to right angles to crank 18. The collar 20 is provided with recesses as at 37 to engage with the securing pin 21 for holding the collar on the shafts 33 and 15 and permitting them to rotate a predetermined distance to retain the trip cranks 34 and 19 in upright position without moving the cranks 32 and 22 and with it the shafts 31 and 23. The cable 46 connected in any suitable manner to the crank levers 47 and 48 mounted on the shafts 15 and 33 respectively insure positive action one with respect to the other. To lock the doors closed or open, crank members 27 and 28 are rigidly mounted on vertical shaft 26 which is rotated by gears 24 and 25, more than half a circle, thus changing the position of cranks 27 and 28 from beyond one dead center to beyond the opposite dead center, cranks 27 and 28 are connected to doors 11 and 12, by pitmen 29 and 30. From this it will be seen that a push or pull action on pitmen 29 and 30 caused by the doors will not rotate shaft 26 or cranks 27 and 28—which are beyond dead centre and form the lock.

In Figure 9, is disclosed as at 39, on the gear 24, a rubber cushion or pad to prevent shock and breakage. The modified form shown in Figure 10 is applied to sliding roller garage doors and is operated through gears 24 and 25, to shaft 26 is attached a sleeve 42, instead of hinged doors previously referred to, and consists of a sleeve 40 attached to a door jamb and a cable or rope 41 travelling thereof and attached to a sleeve 42 and to the doors at 43 and 44 and passing over the sleeve 40. The sleeve 42 in operation is rotated, winding the cable 41 on one side and unwinding it on the other side to open the doors. To close the doors the above action is merely reversed.

In Figure 11 my device is shown as applied to doors in a narrow alley way where under ordinary circumstances the device would obstruct traffic. In this modified

form the spring actuated trip crank 34 is used inside and outside the garage thus eliminating the cranks 18 and 19 so that, as shown by the lines in Figure 2 a car driving up the alley way passes over the outside crank 13 forcing it down without affecting the doors. The car is then backed over the same crank forcing it back down thus rotating the gears 24 and 25 to open the doors. When the car is backed out of the garage it is driven over the crank closing the doors and locking them.

As many changes could be made in the above construction and many apparently widely different embodiments of my invention within the scope of the claims, constructed without departing from the spirit or scope thereof, it is intended that all matter contained in the present specification and accompanying drawings shall be interpreted as illustrative and not in a limiting sense.

What I claim as my invention is:

1. In mechanism of the character described the combination with a door for a garage or the like of a vertical shaft having a gear thereon, crank arms connecting the shaft with the door and means for rotating the shaft at a distance therefrom, comprising a rotatably mounted gear adapted to mesh with the gear on the shaft, a rotatably mounted horizontal shaft, a trip member keyed on said shaft, a rod connecting the second gear with said shaft whereby, on pressure being exerted on the trip member, the horizontal shaft is rotated to rotate the vertical shaft to open or close the door.

2. In a device of the character described and in combination with a door, a shaft having a gear thereon, crank arms rigidly connecting the door with said shaft, a second gear adapted to mesh with the aforementioned gear to rotate the shaft, link rods connecting the second gear with each of said shafts, crank arms rigidly mounted on the horizontal shafts and adapted, on pressure being exerted to rotate the vertical shaft to open and close the door.

3. In a device of the character described, a rotatably mounted horizontal shaft, a crank rigidly mounted thereon, a slotted sleeve on said shaft, a pin adapted to engage with the shaft and with the slots in the sleeve to permit partial rotation of the shaft, a vertical shaft having a gear thereon and a gear rotatably mounted to mesh with said gear and a rod connecting the sleeve on the first mentioned shaft with the second mentioned gear.

4. In automatic door opening and closing mechanism of the character described, a trip member susceptible to pressure exerted by the wheels of a vehicle, comprising a rotatable shaft, a crank rigidly mounted on said shaft, spring actuating means for said crank to normally hold it in a vertical position, whereby, on the crank being pressed

to a horizontal position the shaft is rotated and on the pressure being released the shaft automatically returns to its normal position, mechanism operatively connecting the shaft with the door and means provided on the shaft associated with the connecting means whereby the shaft on being released is adapt-

ed to partially rotate without operating the means connecting it to the door operating means. ¹⁰

In witness whereof I have hereunto set my hand.

PERCY ROBERT DOBSON.
